UNITED STATES PATENT OFFICE

150,814

DESIGN FOR A CARTON

Charles S. Smith, Arlington, Va.

Application March 19, 1946, Serial No. 127,654

Term of patent 14 years

(Cl. D58—13)

To all whom it may concern:

Be it known that I, Charles S. Smith, a citizen of the United States, residing at Arlington, in the county of Arlington and State of Virginia, have invented a new, original, and ornamental Design for a Carton, of which the following is a specification, reference being had to the accompanying drawing, forming part thereof.

Figure 1 is a perspective view of a carton, showing my new design.

Figure 2 is a top plan view thereof.

Figure 3 is a front elevation thereof, and

Figure 4 is a rear elevation thereof.

I claim:

The ornamental design for a carton, as shown.
CHARLES S. SMITH.
